C. E. MCGILL.
SPINDLE RETAINER.
APPLICATION FILED DEC. 6, 1920.

1,383,000.

Patented June 28, 1921.

FIG. 1.

FIG. 2.

FIG. 3.

INVENTOR

Charles E. McGill

BY

G. E. Beach

ATTORNEY

UNITED STATES PATENT OFFICE.

CHARLES E. MCGILL, OF BINGHAMTON, NEW YORK.

SPINDLE-RETAINER.

1,383,000.

Specification of Letters Patent. Patented June 28, 1921.

Application filed December 6, 1920. Serial No. 428,597.

To all whom it may concern:

Be it known that I, CHARLES E. MCGILL, a citizen of the United States, residing at Binghamton, county of Broome, and State 5 of New York, have invented certain new and useful Improvements in Spindle-Retainers, of which the following is a specification.

This invention relates to attachments for 10 retaining the spindles of spinning machines, or the like, to prevent them from being lifted from the bolster when removing a bobbin therefrom; and is particularly suited for use in connection with spindles whose bolsters 15 are resiliently held upon their supports.

The objects of this invention are to provide such a retainer which may be securely locked in holding position, which may be readily released and relocked without the 20 use of any tool or implement and by a simple manipulation thereof, which is durable and is inexpensive to manufacture, and which may be readily applied to existing spindles.

25 Other objects of this invention will be in part obvious and in part more fully described in the following specification and more particularly pointed out in the annexed claims.

30 This invention will be best understood by reference to the accompanying drawing in which—

Figure 1 is an elevation of a typical spindle and its supporting structure with this 35 invention applied thereto;

Fig. 2 is a plan view of the parts shown by Fig. 1 showing the retainer in unlocked position; and

Fig. 3 is a plan view of the supporting 40 bracket and the retainer of Fig. 2, showing the depending stud of the bolster in cross section, the retainer being locked in retaining position.

Referring to Figs. 1 and 2, the spindle 21 carries the pulley 22 having an annular 45 flange 23 at the lower end thereof. Said spindle is journaled to the bolster 24, which bolster rests upon the retainer plate 25. Said plate rests upon the supporting bracket 26 which bracket has an upwardly extending 50 pin 27.

A depending stud 28 extends from the under side of the bolster 24, through an opening provided therefor through the plate 25 and support 26; and the lower end of said 55

stud carries the nut 29, between the upper face of which nut and the under side of the support 26, the spring 30 is so applied as to resiliently draw the bolster 24 toward the support 26. A notch 31 is provided in the 60 bolster 24 for receiving the pin, so that said pin 27 may serve to suitably limit relative rotative movement therebetween.

An upturned projection 32 is carried by the plate 25, the free end 33 of said projection being disposed substantially parallel to the main portion of the plate 25 and spaced slightly above the flange 23, so as to provide a suitable running clearance therefrom. Said end 33 is so formed that it may 65 overlap a suitable portion of the flange 23, and so that, when so overlapping said flange, said end may prevent the spindle 21 from being lifted from the bolster 24.

Referring now more particularly to Fig. 75 3, it will be seen that the elongated opening 34 is so formed as to receive both the stud 28 and the pin 27; the end 35 of said opening being so positioned with relation to the end 33 of the projection 32 that, when said 80 end 35 rests against the stud 28, such end 33 will overlie the flange 23 and will be separated from the pulley face 22 by a suitable running clearance.

The portion of the opening 34 which is 85 adjacent to the pin 27 comprises the locking ledge 36 and the releasing slot 37. Said ledge being so formed that, when the end 35 rests against the stud 28, as just described, the plate 25 may be rotated around said stud 90 95 so as to carry the ledge 36 outside of the pin 27, and said plate 25 will be thereby locked against transverse movement thereof; and said slot 37 is so formed that, when the plate 25 is so rotated around the stud 28 as to present said slot to the pin 27, said plate 25 may be moved transversely to an extent sufficient to carry the end 33 out of the path of the flange 23, and will therefore permit the spindle 21 to be lifted off from the bolster 24.

In the use of this invention, the retainer plate 25 is normally positioned as shown in Figs. 1 and 3, said plate being locked against transverse movement by the engagement of the locking ledge 36 with the pin 27, and being further held against movement relatively to the bolster 24 by the frictional engagement of the under side of said bolster with the upper side of said plate. The end 105 110

33 is therefore securely retained in such relation to the flange 23 as to prevent the removal of the spindle 21 from the bolster 24, although no part of said retainer plate normally touches any part of said spindle.

If it is desired to remove the spindle 21 from the bolster 24, the plate 25 should be rotated clockwise until the slot 37 is presented to the pin 27, and the plate 25 should 10 thereupon be moved transversely, to the position indicated by Fig. 2, thereby withdrawing the end 33 from the path of the flange 23.

When it is desired to again lock the spindle 21 in position upon the bolster 24, the 15 plate 25 should be moved transversely until the end 35 of the opening 34 rests against the stud 28, and said plate should thereupon be rotated around said stud, in counter-clockwise direction until the slot 37 is with- 20 drawn from the pin 27.

It is evident that, should the pin 27 be carried by the bolster 24 (instead of by the bracket 26, as shown), such pin would nevertheless perform its intended functions in an 25 effective manner, and that, should such pin be entirely dispensed with, other features of this invention could nevertheless be advantageously employed, as the friction applied to the opposite sides of the plate 25 by the 30 bolster 24 and bracket 26 could be relied upon for holding said plate against transverse movement thereof. It is also evident that the functions of the pin 27 might be readily consolidated with those of the stud 35 28, as will be well understood by those skilled in this art.

Various other changes may also be made in the number, form and arrangement of the parts shown without departing from the 40 spirit of this invention; and what I therefore claim and desire to secure by Letters Patent of the United States of America is:

1. The combination of a vertical spindle, a bolster upon which said spindle is journaled, a supporting member for said bolster, and a retainer for said spindle frictionally held between said bolster and said member.

2. The combination of a vertical spindle, a bolster upon which said spindle is journaled, a supporting member for said bolster, a retainer for said spindle frictionally held between said bolster and said member for movement into either an effective or an ineffective position with relation to said spindle, and means other than such frictional engagement for holding said retainer against movement from its effective to its ineffective position.

3. The combination of a vertical spindle, a bolster upon which said spindle is journaled, a retainer for said spindle frictionally secured to said bolster for relative movement around and transversely to the axis of said spindle, and such relative construction and arrangement of parts that said retainer

may be moved transversely to an effective or an ineffective position and so that said retainer may be rotated, while in its effective position, so as to permit or prevent transverse movement thereof.

70

4. The combination with a vertical spindle having an annular flange adjacent to the lower end thereof, a bolster member upon which said spindle is journaled, and a bracket member for supporting said bolster,—of a plate frictionally held between said bolster and said bracket and movable relatively thereto, and an upturned projection carried by said plate, the free end of said projection being adapted to overlap the 80 upper face of said flange.

5. The combination with a vertical spindle having an annular flange adjacent to the lower end thereof, a bolster member upon which said spindle is journaled and a bracket 85 member for supporting said bolster,—of a projection carried by one of and extending across the planes of the adjacent faces of said members, a plate frictionally held between said adjacent faces for movement 90 therebetween transversely to the axis of said spindle and so formed that such transverse movement may carry a portion thereof into or out of the path of said flange, and such relative construction and arrangement of 95 said plate and said projection that, while such portion of said plate is in the path of said flange, said plate may be moved either to lock it against or to permit movement to withdraw such portion from said path.

100

6. The combination of a vertical spindle having a pulley face carrying an annular flange, a bolster member upon which said spindle is journaled, a stud depending from the lower face of said bolster, a retainer plate having an opening therethrough for said stud, said plate being so formed that one portion thereof provides a support for the lower face of said bolster and another portion thereof forms a lug normally disposed adjacent to said pulley face above said lug, a support for said plate having an opening therethrough for said stud, and a spring applied between said stud and the lower side of said support.

115

7. The combination with a vertical spindle having an annular flange adjacent to the lower end thereof, a bolster member upon which said spindle is journaled, and a bracket member for supporting such bolster,—of an upwardly extending projection carried by said bracket in position to engage the said bolster to prevent relative movement therebetween, a retainer for said spindle comprising a plate having a recess therethrough for receiving said projection, said recess being so formed with relation to said projection as to permit movement of said retainer transversely to or concentric with the axis of said spindle, such transverse 125

120

130

movement being arranged to govern the effectiveness of said retainer with relation to said spindle and such concentric movement being arranged to afford locking means for 5 governing the transverse movement of said retainer from its effective to its ineffective position.

8. The combination of a vertical spindle having a pulley face carrying an annular 10 flange, a bolster member upon which said spindle is journaled, a supporting bracket member for said bolster having an opening therethrough, a downwardly extending part carried by said bolster member and extending 15 through said bracket member, a spring for urging said members toward one another, a pin carried by said bracket member and so engaging said bolster member as to suitably limit rotative movement thereof 20 with relation to said bracket member, and a plate frictionally held between said members and extending above said flange for limiting the movement thereof away from 25 said bolster, said plate being recessed for said part and said pin so as to permit movement of said plate transversely to said spindle out of the path of the flange and so as to permit rotation of said plate around

said recess to a position where it will be locked against such transverse movement. 30

9. As an article of manufacture, an attachment for retaining a spindle comprising a plate adapted for insertion between a bolster and the support provided therefor, said plate having an elongated opening therethrough 35 for a stud extending from such a bolster and having an extension for limiting movement of the spindle away from such bolster.

10. As an article of manufacture, an attachment for retaining a spindle comprising a plate adapted for insertion between a bolster and the support provided therefor, said plate having an elongated opening therethrough for a stud and for a pin extending from such a bolster, and having an 40 extension for limiting movement of the spindle away from such a bolster, said opening being so formed as to permit transverse movement of said plate to effect release of the spindle when said plate is in a certain 45 position with relation to such pin and to prevent such transverse movement when said plate is not in such relative position. 50

In witness whereof, I hereunto subscribe my name, this 30 day of November, 1920. 55
CHARLES E. MCGILL.
